CLAIM

The ornamental design for an electrical receptacle tester, as shown and described.

DESCRIPTION

FIG. 1 is a perspective view taken from the front, top and right side of an electrical receptacle tester in accordance with our new design;

FIG. 2 is a perspective view taken from the back, top, and left side of the electrical receptacle tester of FIG. 1;

FIG. 3 is a right side elevation view of the electrical receptacle tester of FIGS. 1 and 2;

FIG. 4 is a top plan view of the electrical receptacle tester if FIGS. 1-3;

FIG. 5 is left side elevation view of the electrical receptacle tester of FIGS. 1-4;

FIG. 6 is a bottom view of the electrical receptacle tester of FIGS. 1-5;

FIG. 7 is a back view of the electrical receptacle tester of FIGS. 1-6; and,

FIG. 8 is a front view of the electrical receptacle tester of FIGS. 1-7.

The broken lines shown are included for the purpose of illustrating portions of the electrical receptacle tester that form no part of the claim. The shading lines in the drawings show contour and are not intended to indicate surface orientation.

1 Claim, 3 Drawing Sheets
